(57) **CLAIM**

The ornamental design for a skin therapy device, as shown and described.

DESCRIPTION

FIG. 1 is a top, front, right perspective view of a skin therapy device, showing my new design;

FIG. 2 is a bottom, rear, left perspective view thereof;

FIG. 3 is a top, front, right perspective view shown in a used condition, for clarity of disclosure;

FIG. 4 is a front elevation view of a skin therapy device;

FIG. 5 is a rear elevation view thereof;

FIG. 6 is a left side elevation view thereof;

FIG. 7 is a right side elevation view thereof;

FIG. 8 is a top plan view thereof; and,

FIG. 9 is a bottom plan view thereof.

The broken lines shown in the drawings illustrate portions of the skin therapy device that form no part of the claimed design.
